UNITED STATES PATENT OFFICE.

FREDERICK WILLIAM DURHAM, OF STATION ROAD, BARNET, COUNTY OF HERTS, ENGLAND.

HAT-LINING.

SPECIFICATION forming part of Letters Patent No. 349,633, dated September 21, 1886.

Application filed April 19, 1886. Serial No. 199,388. (No model.) Patented in England February 6, 1886, No. 1,781.

To all whom it may concern:

Be it known that I, FREDERICK WILLIAM DURHAM, a citizen of England, residing at Station Road, Barnet, in the county of Herts, 5 England, have invented a new and useful Improvement in Hat-Linings, (for which I have made application in Great Britain, February 6, 1886, No. 1,781,) of which the following is a specification.

10 It is often desirable to change the leather lining of the lower part of a hat when that lining has become soiled or otherwise damaged.

15 My invention relates to the constructing and fixing of a hat-lining in such a manner that, no stitching being required for fixing it, it can readily be removed and a fresh lining can at once be put in its place. For this purpose I make and fix the lining as I will describe and claim, referring to the accompanying drawings.

20 Figure 1 is a view of the lining spread out, this view being taken at the back—that is to say, at the side which, when the lining is in place, is next the wall of the hat. Fig. 2 is a part section through the lower part and brim of the hat.

25 A is a thin flexible strip of steel or other suitable stiff material, which I fix by stitching at its edge b to the edge of the leather band 30 B. This may be accomplished by providing the strip A, if of metal, with a line of perforations adjacent to one edge, through which the threads may be passed to connect the strip with the edge of the leather band, after the ordinary manner of sewing; but obviously, 35 if the strip is not of metal, but of such stiff material as to permit a needle to penetrate it, the leather band and strip can be sewed edge to edge by an ordinary needle and thread.

40 Other methods of connecting the edges of the strip and band together by stitching will readily suggest themselves.

45 On the strip A, I pivot by riveted pins two or more hooks, C, which can be turned on their pivot pins, either up, as shown at C, or down, as indicated at C'. The free ends of the hooks are made with sharp points or serrations, which can pierce the wall of the hat.

50 For putting in the lining, the hooks C are turned up and the leather band B is turned down, as indicated at B', Fig. 2, and the hooks C being pushed into the wall of the hat above

the upper edge of the strip A, the leather band B is turned in, the lining being thus fixed in position.

55 It is of advantage to make the points of the hooks C sufficiently long to penetrate through the wall of the hat, so as to enter a hat-band, E, when such band is worn, the band E being thus prevented from rising out of its place.

60 Heretofore a sweat-band has been provided around its lower edge with a strip of metal having attached spurs, which are either riveted to or driven through the hat-body. Such, therefore, I do not broadly claim.

65 Having thus described the nature of my invention and the best means I know of carrying it out in practice, I claim—

1. In a hat-lining, the combination, with the leather band B and the steel or other stiff strip A, the two connected edge to edge, of the swinging hooks C, pivoted at one end to the strip between the latter and the band, and having their hooked ends pointed to penetrate the hat-body above the upper edge of the strip, substantially as shown and described.

70 2. In a hat-lining, the combination, with the leather band B and the steel or other stiff strip A, the two united edge to edge by a line of stitching, of the swinging hooks C, pivoted to the strip between the latter and the band, and having their hooked ends pointed to penetrate the hat-body above the upper edge of the strip, substantially as described.

75 3. The combination, with a hat, of the leather band B, the steel or other stiff strip A, having its edge secured to the edge of the band by a line of stitching, and the swinging hooks C, pivoted at one end to the strip between the latter and the band, and having their hooked ends pointed and penetrating the hat-body above the upper edge of the strip, substantially as described.

80 4. In testimony whereof I have signed my name to this specification, in the presence of two subscribing witnesses, this 7th day of April, 85 A. D. 1886.

FREDERICK WILLIAM DURHAM.
